UNITED STATES PATENT OFFICE.

OSCAR SMIEDEL, OF CHICAGO, ILLINOIS.

SPRAYING-NOZZLE.

1,273,685.

Specification of Letters Patent.

Patented July 23, 1918.

Application filed March 27, 1917. Serial No. 157,762.

To all whom it may concern:

Be it known that I, OSCAR SMIEDEL, a citizen of the United States, residing at Chicago, in the county of Cook and State of Illinois, have invented certain new and useful Improvements in Spraying-Nozzles, of which the following is a specification.

The present invention has to do with certain improvements in spraying nozzles for use in connection with garden hose and the like, although it will presently appear that the features of the present invention are in no wise limited to this particular class of service.

15 The main objects of the present invention are to provide a very simple form of construction of spray nozzle, but a form which nevertheless will be very flexible and can be very easily handled by the user. Also to so 20 construct the nozzle that the spray may be very flexibly controlled both as to volume and character.

Other objects and uses of the invention will appear from a detailed description of 25 the same which consists in the features of construction and combinations of parts hereinafter described and claimed.

Referring to the drawings:

Figure 1 shows a front or end view of the 30 spray nozzle with the valve plug turned into such a position as to partially open one of the orifices;

Fig. 2 shows a vertical section taken on the line 2—2 of Fig. 1, looking in the direction 35 of the arrows;

Fig. 3 shows a horizontal section taken on the line 3—3 of Fig. 2, looking in the direction of the arrows;

Fig. 4 shows a side elevation of the valve 40 plug; and

Fig. 5 shows an end view corresponding to Fig. 4.

Referring to the construction shown in the several figures, the nozzle is conveniently 45 provided with an elongated portion 6 which serves as a handle by means of which the nozzle is conveniently grasped and manipulated by the operator. The rear end of this portion is threaded at 7 for attachment to 50 the terminal of the garden hose in the usual manner. Near its front end the elongated portion 6 is enlarged as at 8 for the accommodation of the plug valve which is shown

in detail in the various figures and separately in Figs. 4 and 5. This enlarged portion 8 is provided with a circular tapered socket within which the plug valve 9 seats. The front end 10 of the nozzle is preferably flared or spread out in the manner shown in the several figures so as to permit a free 60 discharge of the spray, while at the same time giving the nozzle a finished and completed appearance. A discharge orifice 11 best shown in Figs. 1 and 3 occupies a central position within the flared portion 10. 65

The plug valve itself is conveniently made of circular tapered form. It has the central stem 12 which passes through the rear wall 13 of the member 6. The stem 12 is somewhat contracted in its portion 14 where it 70 passes through the wall 13, and said portion 14 is also tapered so as to make a water-tight fit at the same time that the body portion of the plug valve is seated in water-tight manner. A nut 15 and washer 16 are placed on 75 the contracted portion 14 of the stem 12 in the manner which will be readily understood from the figures.

In its central portion, the plug valve is provided with a pair of circular partitions 80 17 and 18 which provide a narrow slot 19 between them. Around the periphery of the wall of the plug are the openings 20, 21, 22, and 23 of graduated sizes. The opening 20 is shown as being circular, whereas the 85 openings 21, 22, and 23 are each in the form of an elongated slot. Examination of Fig. 4 reveals the fact that these slots are of graduated widths. The opening 11 in the front end of the member 6 is of sufficient 90 width to accommodate the entire stream delivered by the widest one of the openings in the plug valve 9. The partitions 17 and 18 are warped or tapered or varied in contour in such a manner that adjacent to each of 95 the openings 21, 22, and 23, the width of the space 19 is just equal to the width of the said opening, the partitions 17 and 18 tapering at points between the openings, as shown in Fig. 4. Consequently, the water 100 delivered through any one of the openings 21, 22, or 23 is compressed or drawn into a sheet of the same width as the opening through which it is to be delivered.

The partition 17 adjacent to the open side 105 of the plug valve is provided with an inner

orifice or perforation of somewhat larger size than the stem 12, so as to leave a circular or annular opening 24 all around said stem. The elongated member 6 is provided 5 with a bulged portion 25 in one side, which bulged portion is opposite to the edge or periphery of the plug valve so as to leave a space or opening 26 through which the water may enter into the open side of the plug 10 valve and then find its way through the annular opening 24 into the space 19 between the partitions 17 and 18. Thus the major portion of the water enters the space 19 by way of the annular opening 24, although it 15 will be apparent that other portions of water may also enter said space through any of the openings 20, 21, 22, and 23, which may be in communication with the space within the member 6.

20 Assuming the plug valve to be turned into a position for the delivery of water through one of the openings, the following action will be observed: The water delivered through said opening will flow circularly around the space 19 in both directions toward the delivery opening, so that two 25 opposing bodies of water will thus be created. As these two opposing bodies of water meet in or adjacent to the opening through which they are being discharged, they will so conflict as to cause a flat spray to be delivered, the plane of said spray lying at right angles to the plane of the space 19. This fact is well 30 illustrated in Figs. 2 and 3, in which the form of the spray is shown.

Extending into the body of the passage 19 is a short tube or nipple 27 through 40 which the water is delivered to the circular hole 20, thus insuring the delivery of a circular stream of water through the hole 20 when said hole is brought opposite to the opening 11.

In the construction of the plug valve, the 45 various openings 21, 22, and 23 may be made of such size that as the plug valve is turned from one position to another, the stream will not be entirely shut off except when the valve is turned to a point between the openings 20 and 21. The plug valve is conveniently provided with a handle 28 by means of which it is turned.

The flared portion 10 may be of any desired contour, but for convenience I have 55 illustrated the same as being circular. At its lower end it communicates with the end wall 29 of the member 6, within which end wall is formed the delivery opening 11. The inner surface of the flared portion 10 should 60 be of such contour and size as to permit the free delivery of the spray without interference.

While I have herein shown and described 65 only a single embodiment of the features of my invention, still it will be understood that

I do not limit myself to the said embodiment, except as I may do so in the claims.

I claim:

1. In a device of the class described, the combination with a valve socket member having a hose connection at one end and a transverse partition at the other end, there being a rectangular discharge orifice within said partition, of a circular valve member seated within the socket of said socket member, said circular valve member having a plurality of slotted openings in its periphery, said slotted openings being of graduated width, a pair of partitions within the valve member providing therebetween a circular passageway in communication with said slotted openings, the width of said passageway adjacent to each slotted opening being substantially the same as the width of such opening, one of said partitions being provided with an annular central opening for the admission of water into the said circular passageway, and the socket member being suitably formed to permit a free movement of water to said annular opening, substantially as described. 75 80 85 90

2. In a device of the class described, the combination with a valve socket member having a hose connection at one end and a transverse partition at the other end, there 95 being a discharge orifice in said transverse partition, of a circular valve member seated within the socket member at a point adjacent to said partition, said valve member being provided in its periphery with a plurality of slotted openings of graduated sizes adapted to register with the discharge orifice, a pair of partitions within the valve member on opposite sides of the slotted openings, said partitions serving to provide a 100 circular passageway in communication with all of the slotted openings, one of the partitions being provided with an annular central opening for the admission of water into said circular passageway, and the valve 110 socket member being suitably formed to permit a free flow of water to said annular opening, substantially as described. 105 110

3. In a device of the class described, the combination with a valve socket member having a transverse partition at one end, there being a discharge orifice within said partition, of a circular valve member working within the said member at a point adjacent to said partition, there being a plurality of peripheral slotted openings in the valve member adapted to register successively with the discharge orifice, and a pair of partitions within the valve member serving to provide therebetween a circular passageway in communication with all of the slotted openings, substantially as described. 115 120 125

4. In a device of the class described, the combination with a valve socket member having a transverse partition in one end, 130

there being a discharge orifice in said partition, of a circular valve member working in the socket member at a point adjacent to said partition, there being a slotted peripheral opening in said valve member adapted to register with said discharge orifice, a pair of separated partitions within the valve member providing therebetween an annular passageway in communication with the slotted opening, and there being an opening for 10 the admission of water to said passageway, substantially as described.

OSCAR SMIEDEL.
